UNITED STATES PATENT OFFICE.

THOMAS J. HARTMAN, OF CHICAGO, ILLINOIS.

FOOTBALL HELMET.

Application filed June 1, 1922. Serial No. 565,024.

To all whom it may concern:

Be it known that I, THOMAS J. HARTMAN, a citizen of the United States, and a resident of the city of Chicago, county of Cook, and 5 State of Illinois, have invented certain new and useful Improvements in Football Helmets, of which the following is a specification.

My invention relates to new and useful 10 improvements in football helmets, and more particularly to helmets of the type having sections of armor yieldably connected together to permit various adjustments thereof by spacing said sections with respect to 15 each other, and has for its object the provision of protective means for spanning the interstices between said sections without interfering with the adjustability of the sections.

20 Other objects will appear hereinafter.

The invention consists in the combinations and arrangements of parts hereinafter described and claimed.

The invention will be best understood by 25 reference to the accompanying drawings forming a part of this specification, and in which,

Fig. 1, is a side elevation of the invention, Fig. 2, is a section on line 2—2, Fig. 1, and

30 Fig. 3, is a section on line 3—3, Fig. 1.

As illustrated in the drawings only one side of the helmet is shown, and only one side thereof will be specifically referred to, but, of course, it will be understood that 35 both sides of the helmet are substantially identical. The helmet preferably comprises a crown piece 10 provided with a rear shield 11, which includes ear flaps 12 preferably formed integral therewith, such shield 11 being secured to the crown piece 10 by straps 30, or by any other suitable means. The outer face of the shield 11 consists of heavy leather or other suitable material, and secured to the inner face thereof is a layer 15 of padding, such padding being preferably secured to the outer face 14 of the shield by stitching which extends along the edges of the shield 11 and the ear flaps 12, as shown, such stitching being interrupted on the forward portion of each of the ear flaps 12 at 45 a point spaced from the upper end of the shield 11, as shown at 16 thereby forming a pocket or passageway 17 between the padding 15 and the outer face 14 of the shield. 50 Secured to the crown piece 10, preferably intermediate its ends, by means of a strap

18 is a front shield 19, the free ends of which are preferably disposed adjacent the pockets 17 formed in the shield 11, as shown. The shield 19 also comprises a heavy outer layer 60 20 of leather or other material, and an inner layer 21 of padding, there preferably being a lining 22 disposed over the padding 21, as shown. The ends of the shield 19 are preferably connected to the ear flaps 12 by 65 means of elastic strips 23, the end 24 of each strip being preferably held between the outer and inner layers of the shield 19 by the stitching which secures said layers together, and the end 25 of the strip 23 preferably extends into the pocket or passageway 70 17, and is secured by a transverse line of stitching 26, as shown.

From the foregoing it will be seen that the size of the helmet may be varied as desired by moving the ends of the shield 19 away from the ear flaps 12. A helmet such as described has a very serious defect in that when the adjacent ends of the shield are separated to permit adjustment of the 80 armored sections of the helmet to larger sizes, a space is left between the ends of the sections, which is entirely unprotected and as this space is of necessity situated in the vicinity of the temple of the wearer it 85 becomes important to afford protection to such portion without interfering with the adjustability of the helmet. This I have accomplished by providing a member 27, preferably in the form of a tongue and of 90 heavy material, which is adapted to span the interstice between the ear flap 12 and the shield 19, so as to provide protection to the wearer at this point. As illustrated, the tongue 27 preferably has one end secured between the inner and outer layers 21 and 20 by means of stitching 28, as shown in Fig. 2, and the opposite end of the tongue 27 projects into the pocket 17, and is slidably held 95 therein. When used in connection with the elastic strip 23, the tongue 27 is disposed on the outer side of said elastic strip. By this arrangement it is evident that when the shield 19 is spaced from the ear flap 12 in 100 order to permit adjustment of the helmet to larger sizes, ample protection is afforded the wearer by the tongue 27 which provides a heavy piece of material which extends across the space between the shield and the ear flap, such tongue in no way interfering 105 with the adjustability of the helmet.

While I have illustrated and described the

2
preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

10 Having described my invention, what I claim as new and desire to secure by Letters Patent is:

15 1. A football helmet comprising armored sections adjustably connected together, each of which consists of an inner layer of padding and an outer layer of armor; and a tongue of armor material secured between the layers of one of said sections, said tongue slidably projecting between the layers 20 of the other of said sections and effectively covering the interstices between said sections, the stitching for holding said layers

together being interrupted to form a passageway for said tongue.

2. A football helmet comprising armored sections adjustably connected together, each of which consists of an inner layer of padding and an outer layer of armor; a tongue of armor material secured between the layers of one of said sections, said tongue slidably projecting between the layers of the other of said sections and effectively covering the interstices between said sections, the stitching for holding said layers together being interrupted to form a passageway for said tongue; and an elastic strip secured on the inner side of said tongue having one end secured between the layers of said first mentioned section, and having its opposite end extending through said passageway and being secured by another line of stitching.

In testimony whereof I have signed my name to this specification.

THOMAS J. HARTMAN.
